UNITED STATES PATENT OFFICE.

MOWRY S. WILLIAMS, OF SYRACUSE, NEW YORK, ASSIGNOR OF ONE-HALF TO JOHN R. CLANCY, OF SYRACUSE, NEW YORK.

SPARK-PLUG.

1,337,679.

Specification of Letters Patent.

Patented Apr. 20, 1920.

Application filed July 5, 1916. Serial No. 107,538.

To all whom it may concern:

Be it known that I, Mowry S. Williams, a citizen of the United States of America, and resident of Syracuse, in the county of Onondaga, in the State of New York, have invented new and useful Improvements in Spark-Plugs, of which the following, taken in connection with the accompanying drawings, is a full, clear, and exact description.

10 This invention relates to certain improvements in spark plugs as a part of an electric ignition system for internal combustion engines, the main object being to enable the same plug to be used under widely varying conditions as to sizes of the cylinders, degree of electric energy in the ignition system and the amount, quality and nature of the fuel for the purpose of obtaining a maximum power and working efficiency of 15 the engine with a minimum quantity of fuel.

15 This involves the following structural features and advantages:

First,—the adjustment of one of the terminals from the exterior while the engine 20 is in operation to vary the spark gap according to the requirements under the varying conditions previously mentioned, and also for cleaning purposes in bringing such terminal into wiping contact with the other 25 terminal or bushing to remove carbon and other foreign matter which may accumulate thereon.

Second,—the return-bending of the adjustable terminal to prevent as far as possible 30 the accumulation of oil or other foreign matter on the extremity thereof adjacent the spark gap.

Third,—the provision of a gas-tight joint 35 between the adjustable terminal and insulator in which it is mounted, and

Fourth,—the construction of the insulator and other parts of the spark plug in such manner as to greatly increase its durability and security of adjustment.

40 Other objects and uses will be brought out in the following description.

In the drawings—

Figure 1 is an elevation of a spark plug embodying the features of my invention.

50 Fig. 2 is a longitudinal sectional view of the same.

Fig. 3 is a transverse sectional view taken on line 3—3, Fig. 1.

As illustrated, this spark plug comprises

an electrically conductive bushing —1— of 55 metal having one end threaded internally at —2— and its opposite end threaded externally at —3— and provided with an annular flange or shoulder —4—, the intermediate portion between the threaded portion —2— and annular shoulder —4— being formed with a tapering bore —5— for receiving the correspondingly tapered end of an insulating sleeve —6— which is held in place with its lower end against the 60 shoulder —4— by an externally threaded follower —7— engaging the internally threaded portion —2—, as shown more clearly in Fig. 2.

The insulating sleeve —6— is preferably 70 circular in cross section throughout its length and extends some distance above the upper end of the follower —7— when adjusted for use, said insulating sleeve being provided with a central lengthwise opening —8— therethrough from end to end, the upper end of which is threaded at —9— to receive a threaded electric conductor or spindle —10— which extends entirely through and beyond the opposite ends of 80 said insulating sleeve.

The lower end of the spindle is formed with a return-bend —11— terminating in a spark terminal —12— which extends axially of the plug from the return-bend —11— toward and into close proximity to the adjacent lower end of the bushing —3— to form a spark gap —13—.

The extremity of the spark terminal —12—, therefore, lies directly under the annular shoulder —4— so that by turning the spindle —10— in one direction or the other in the sleeve —6—, the extremity of the terminal —12— may be closer to or farther from the adjacent end of the bushing —3— to vary the spark gap —13— according to the requirements under varying conditions, such as the size of the cylinder, the degree of electric energy of the ignition circuit, or the amount or quality of the fuel, or 90 this rotary and axial adjustment of the spindle —10— may be used to bring the end of the terminal —12— into wiping contact with the adjacent end of the bushing —3— to clean the adjacent surfaces from 95 accumulations of carbon or other foreign matter.

This adjustment of the spindle may be

made by applying a suitable tool to the upper end thereof while the engine is in operation.

One of the objects of the return-bend 5 —11— at the junction of the spark terminal —12— with the main body of the spindle —10— is to allow any oil or other foreign matter which may tend to accumulate on said terminal to flow away from the spark- 10 15 10 ing point thereof toward the bend from which it may be dropped into the cylinder, thereby reducing to a minimum one of the chief causes of inefficient sparking.

When the spindle —10— is properly adjusted, it is firmly locked to the insulator —6— against relative movement by a suitable cap-nut —14— engaging the threaded portion of the spindle and upper end of the insulator.

20 A packing —15— of asbestos or equivalent insulating material is interposed between the adjacent ends of the cap —14— and insulator —6— and is preferably screwed upon the threaded portion of the 25 spindle to fit tightly thereon and thereby prevent leakage of gas through the opening in the insulator along the threads of said spindle.

The upper end of the spindle may be 30 wired in any well-known manner to the source of electric energy forming a part of the ignition system, such wire being held in place by a clamping nut —16— and washer —17— engaging the upper threaded 35 end of the spindle which projects some distance above the clamping nut —16— when the spark plug is adjusted for use.

The bushing —1— which constitutes a co- 40 operative spark terminal may be screwed into the cylinder of the engine in the usual manner for spark plugs, and is grounded through the cylinder or other parts of the engine or frame of the machine with suitable connections to the opposite pole of the 45 source of electric energy for completing the ignition circuit.

It is to be understood, however, that the

particular manner of connecting the spark plug to the source of electric energy forms no part of my invention and that it may be 50 used with any suitable ignition circuit.

The lower tapering end of the insulating sleeve —6— is provided with an annular groove or channel —18— forming relatively narrow annuli —19— in the tapered bore —5— at opposite ends of the channel to secure a more perfect gas-tight joint, the upper end of the upper annulus —19— forming a shoulder against which the lower end of the follower —7— abuts to firmly lock the insulator to the bushing with its lower end against the annular shoulder —4—.

What I claim is:

A spark plug comprising a tubular metal bushing having its inner end provided with 65 an inturned annular flange, a one-piece tubular insulator having its inner end inserted in the bushing and terminating against said flange and its outer end extending some distance beyond the outer end of the bushing 70 and threaded internally, a threaded member screwing into the outer end of the bushing and engaging the insulator for holding its inner end against said flange, and an electric conductor extending entirely through and 75 beyond the opposite ends of the insulator and having its inner end returned outwardly toward said flange and its outer end threaded and engaged with the internally threaded outer end of the insulator, whereby 80 the turning of the spindle in reverse directions will cause its inner terminal end to rotate around said flange and at the same time will vary the distance between the returned inner end of the conductor and the 85 flange, the threaded engagement between the conductor and insulator serving to hold the conductor in its adjusted position.

In witness whereof I have hereunto set my hand this 23^d day of June, 1916.

MOWRY S. WILLIAMS.
